CONTROLLABLE PITCH PROPELLER

Roland Chilton, Ridgewood, N. J., assignor to
Wright Aeronautical Corporation, a corporation
of New York

Application-February 10, 1938, Serial No. 189,775

8 Claims. (Cl. 170—163)

This invention relates to variable pitch propellers and particularly to propellers for aeronautical engines. A principal object of the invention is to provide improved and simplified blade mounting means wherein the main hub structure is lighter and more compact than in current practice and wherein the production costs are reduced by a simplified geometry of the parts. This is achieved in part by a novel blade mounting comprising an angular contact ball bearing for each blade which, in the preferred embodiment, may be disassembled for detachment of blades, without disturbing the bearing-race connections which may be permanent, or even integral with the associated member.

The invention also includes a novel operating mechanism for the pitch changing function, having advantages in simplicity, strength and compactness and also affording improved and simplified automatic control means.

A further object is to provide auxiliary means which may be incorporated in case the ability to "feather" the propeller is desired.

It is well known that one of the prime difficulties encountered in the development of metal blade propellers has been the destructive effects of resonant vibrations, so that in current practice the sections of the blades and their attachments are far beyond any proportions that can be justified by calculation of the centrifugal and bending forces involved in the transmission of the power to be handled, in the absence of the vibration effects. For example, the development of any specific size of blade to satisfactory resistance to vibratory fatigue failure has been accompanied by a relatively rapid increase in the diameter of the blade at the butt. This has involved a corresponding increase in the diameter of the anti-friction bearings which are normally disposed around the butt or shank of the blade. This great increase in blade weights has correspondingly increased the centrifugal force on the blade bearings with respect to the forces from bending moments due to torque and thrust. With the current proportions of blade weights and blade bearings the base afforded by the bearing diameter is so big and the centrifugal force thereon so high, that the blade is stable in operation against the bending moments to which it is subject. That is to say, if a single ball or roller bearing of current diameter be used to resist the centrifugal pull of the blade the bending moments from torque and thrust on the blade will never be sufficient to completely unload one side of the bearing races, the effects

of the bending moments being merely to modify the load distribution on the balls.

When the engine is idling and subject to irregular running or backfires, the centrifugal force may be insufficient to produce stabilization on a single ring of balls, and, accordingly, in current practice, bearing means spaced axially of the blade are used, the loads on such bearings due to bending moments being regarded as inversely proportional to their effective spacings. It should be noted that, at any given pitch setting, the bending forces due to torque and thrust, and the centrifugal force all increase as the square of the rotational speed, wherefore a blade attachment which is stabilized by centrifugal force at any one speed of rotation, is stable at all other speeds (except for irregular engine running at very low speeds).

One current construction employs a "stack" of annular bearings and, considering the effect of blade bending moments, in the absence of centrifugal force, on this structure, it will be seen that the effective stabilizing base is not merely that due to the axial separation of the end races but is the diagonal dimension between opposite ball elements of the respective end bearings of the stack.

In another currently used construction the hub is provided with extending stubs each having journals of substantial separation axially of the blade which is made hollow to engage the journals which take no part in resisting centrifugal force. The blade is provided with a heavy flange against which is fitted a thrust bearing of necessarily large diameter engaging a heavy flange on a relatively rigid outside hub member. Under operating conditions with the high centrifugal force normally present, this structure is indeterminate as to the distribution of the effects of bending moments between the stubs which apparently are designed to receive them, and the thrust bearing which, when loaded by centrifugal force may resist bending action on the blade more directly than the spaced journals of the stubs. The distribution of load between the stub bearings and the single thrust bearing will depend upon the relative rigidity of these parts, and in practice, the proportions are such that the stub has by far the greater flexibility under these conditions, the stubs in normal operation actually perform little, if any, duty. In the case where the thrust bearing is of roller type, having a flat face, the stubs may take the shearing action due to the tangential effort from the torque. The present invention teaches that

single row angular contact type of bearings are in themselves capable of resisting the tangential loading whereby axially spaced bearings, such as the stub journals or the multiple bearing stack construction, are unnecessary and they are here eliminated with a resulting reduction in weight, bulk and cost.

Objects of the invention are to provide a propeller of the controllable pitch type wherein a simplified form of blade mounting is provided, wherein improved pitch changing means are incorporated, wherein provision is made for feathering the blades, and wherein provision is made for improved lubrication of the propeller mechanism. The invention also provides a novel form of blade construction and mounting for the purpose of minimizing weight and destructive vibration.

The invention will now be better understood with reference to the drawings in which similar numbers indicate similar parts and in which,

Fig. 1 is a section through the axes of one propeller blade and of the hub,

Fig. 2 is a section on the line 2—2 of Fig. 1,

Fig. 3 is a detail axial section through a preferred blade construction and an alternative hub construction,

Figs. 4 to 7 inclusive are blade cross-sections on the line 4—7 inclusive of Fig. 3,

Fig. 8 is an elevation of the hub and blade roots including a fragmentary section,

Fig. 9 is a detail section through part of the hub illustrating wiring connections on the line 9—9 of Fig. 2,

Fig. 10 is a detail view of a ratchet unit,

Fig. 11 is a detail view of a lubricating pump,

Fig. 12 is a perspective view of the alternative hub unit, and

Figs. 13 and 14 are respectively longitudinal and cross-sections through an alternative hub unit.

Referring first to Fig. 1, 10 designates a conventional engine crankshaft or propeller shaft provided with the standard propeller hub mounting cone 12 and splines 14 with which are engaged companion splines on a main hub member 16. In this instance a three-bladed propeller is shown, the hub being provided with three integral annular projections 18 provided with integral ball race or track elements 20 co-operating with balls 22 and a companion track or race 24 formed on a blade sleeve member 28. The races 20 are preferably locally hardened and their formation integrally with the hub 16 is the preferred embodiment of the invention. The prior art shows ball or roller bearing units having individual races which must be secured to the hub as by a split construction thereof and/or screw threaded connections which are eliminated in this invention. The simplification is made possible by the assembly scheme here employed wherein the balls themselves may be disassembled to permit removal of the blade. It will be seen that the inner diameter 30 of the race 24 on the external member 28 is designed to pass the external diameter 32 of the hub race member 20. A suitable hole 34 is provided in the member 18 through which the balls may be withdrawn after the member 28 has been moved inwardly as provided for in the clearance indicated at 36.

In the specific showing of Fig. 1 a standard form of blade 37 having an out-turned flange 38 at the butt struck on a large radius or fillet and this flange is engaged by a split nut 40 screwed into threads 42 in the bearing sleeve member 28.

The nut has a flange 44 which is screwed tightly home, preferably with the interposition of a shim 46. Alternately to splitting the nut 40 this may be passed up the blade before upsetting the flange 38. The blade 37 is provided with a driving plate 48 having splines 50 engaging splines in the bearing sleeve 28, and also a recess accommodating a counter-thrust washer 52 engaging a flat thrust surface formed on the hub race member 18. The shims 46 may be adjusted at assembly to bring the main thrust bearing 22 and the auxiliary or counter-thrust washer 52 to zero back lash when the shoulder 44 of the nut 40 is screwed tight. It will be seen that the ball bearing 22 is of the angular contact type capable of sustaining radial and axial loads.

Considering now a bending force applied to the blade 37 as indicated by the arrow F, it will be seen that such force will (in the absence of centrifugal force) unload the balls on the right hand side of Fig. 1 and apply a thrust force indicated by the arrow T on the right side of the auxiliary thrust washer 52, while an equal and opposite reaction T' will occur on the balls on the left hand side. It will be seen that these reactions occur at diametrically opposed points of the bearings whereby they act at a substantial arm or base comparable to or greater than that afforded by the axial separation of the stabilizing bearings in conventional structures.

It should be clearly understood, however, that under the influence of the normally predominating centrifugal forces, there will be no reactions T on the thrust washer 52 because the force T will be insufficient to completely unload the balls 22 on that side of the bearing because of the predominance of the centrifugal force outwardly along the blade axis. Thus, the effects of bending moments from thrust and torque under normal operation will be to somewhat increase the load on the balls on one side of the bearing 22 and decrease the load on the diametrically opposite balls. Actually, the effect of the combined centrifugal and bending forces is that of shifting the effective pull on the blade to be somewhat eccentric to the axis thereof but with the proportions shown, this eccentricity is small compared to the diameter of the balls 22 which affords an ample base to stabilize the blade under the predominating centrifugal force in despite of the bending moments present.

Before describing the rest of the structure, an alternate and preferred blade construction shown in Fig. 3 will be described. This comprises a non-metallic blade 37—a, preferably of molded material such as phenolic plastic which is molded about a shank or stub 54 provided with buttress serrations 56. This stub is preferably circular at the root and is taperingly flattened as shown in the sections Figs. 4 to 7 inclusive to conform approximately to the general exterior profile of the blade.

The shank 54 has an enlarged conical butt 57 provided with a ball race track 58 engaging balls 22—a which, in turn, engage companion raceways 62 formed integral with the hub 16—a. It will be seen that this bearing structure is merely an inverted disposition of the showing of Fig. 1, the difference being that in this case, the outer or in-turned race member is formed integral with the hub and the inner or out-turned race member is formed integral with the blade shank. In this case, the counter-thrust or stabilizing washer 52—a is engaged by a gear ring 46—a splined to the butt 57 at 64, as shown, and adjusted into

fitted contact with the auxiliary thrust ring 52—a by means of a nut 86. A groove 34—a (Fig. 13) is formed in a thickened portion of the race elements 62 for disassembly of the balls 22a corresponding to the holes 34 of Fig. 1.

The hub 16—a is a part which may be readily fabricated from a block or forging by simple machining operations. The shaft bore *a*, the clearance *b* for pitch changing mechanism and the front bore *c* for the hub nut and associated elements, are formed by axial boring operations. The blade openings *d*, with the ball races 62, are machined by boring operations using a formed cutter, while the formation of exterior of the hub comprises a simple spherical turning operation. The bump *e* is provided to give a greater section thickness at the front of the propeller shaft opening.

The balance of the mechanism now to be described may be used with either of the alternate blade and blade bearing structures already described. Referring first to Fig. 1, a bevel gear tooth quadrant 68 is formed integral with the sleeves 28 (in the case of the embodiment of Fig. 3 the corresponding gear quadrant 68—a is formed integral with the ring 46—a previously described). Meshed with the gear quadrants 68, is a central control gear 70 having an integral sleeve 72 and wormwheel 74 rotatable on a suitable bushing 76 which is in turn supported on a cylindrical extension 78 of a hub nut 80 which engages the standard threads 82 of the engine shaft 10 as shown. The nut 80 engages the hub 16 through an external flange or shoulder 84 while a split ring 86 engaging grooves in the hub 16 and in the nut 80 serves as a puller for removal of the hub.

Surrounding the hub 16 is a split housing, preferably of duraluminum forgings, comprising the forward portion 88 and the rear portion 90 secured together by bolts 92 and to the hub 16 by bolts 94. A lock nut 96 threaded on an extension 97 of the hub nut 80 further clamps this part, the bushing 76 and front housing 88. The split housing 88—90 clamps around oil sealing sleeves 98 (which are not split) and which extend radially inwards around the propeller blade sleeves 28 to define an annular lubricant reservoir within the housing 88—90 in which lubricant is retained by centrifugal force during operation.

Engaged with the wormwheel 74 is a worm 100 integral with a shaft having splines 102 and journals 104 engaged in bushings 106 fitted to bosses 108 formed in the housing 88 (as seen in section Fig. 2). The bushings 106 are screw-threaded at 110 for axial disassembly and the bosses 108 have slots 112 wide enough to permit the worm shaft 102—104 to be withdrawn laterally and inwardly upon removal of the bushings 106.

Mounted for free axial sliding on the splines 102 are fine tooth ratchet members 114 of opposite "hand," spaced and controlled by a semi-circular control sleeve 116 having in-turned end collars 118 of "horse-shoe" formation engaging grooves in the ratchets 114. The controllable ratchets 114 are engageable with companion ratchets 120 formed on hubs 122 of levers 124 extending rearwardly within the housing 88—90 and provided at their right hand ends with a ball member 126 (Figs. 1 and 8) which is in turn engaged in an eye 130 of an eccentric strap 132 rotatable (with the levers 124) upon a stationary eccentric 134 formed integral with a sleeve 136 carrying a bevel gear 138 meshed with and nor-

mally held stationary by, a pinion 140 later to be further described. The sleeve 136 of the eccentric is mounted on a fixed sleeve 142 integral with a flange 144 rigidly bolted to the standard facing 146 provided on the engine for the purpose.

The extreme right hand ends of the levers 124 are provided with flats 148 guided for radial movement in a suitable groove 150 formed in the rear housing 90 (Fig. 8).

On the opposite side of the hub from the worm 100 there is provided a solenoid housing 152 (Figs. 1 and 2) secured by screws 154 in the housing 88 and containing electro-magnetic windings 156—157 by which a floating armature 158 may be energized to move in either direction, by control means later to be described. This solenoid engages a ratchet operating lever comprising the arm 160 depending from a hub 162, pivotally embracing the sleeve 72 of the main bevel gear 70, provided at its upper end with a ball connection 164 which operates the ratchet control sleeve 116. The lever 160 and the ratchet control sleeve 116 are normally retained in the central or neutral position shown (with both ratchets disengaged) by means of a centralizing spring 168.

The rear face of the housing 90 is equipped with an insulating disc 170 secured to the housing by screws 172 and carrying concentric slip rings 174 and 176 connected to respective solenoid coils 156—157 by suitable wiring 159—161 seen in the detail view of Fig. 9. The slip rings 174—176 are engaged by suitable brushes, that for the latter ring being seen in section at 178. These brushes are connected to a suitable battery and electrical switching mechanism (not shown) as by leads 180. The external electric control means to be connected to the wires 180 may be identical with that used in other forms of electrically controlled propellers, usually comprising a switch gear worked by a speed responsive governor to effect constant speed propeller operation. Such extraneous mechanism, however, forms no part of the present invention and need not be further described. The operation of the propeller pitch control mechanism will now be clear as follows:

The mechanism so far described may be used with or without the mechanism associated with the normally stationary pinion 140 which mechanism comprises manually controllable propeller feathering means later to be described. In any event, during normal operation, the eccentric 134 is held stationary and will, in fact, be secured directly to the housing 144 in the case of a non-feathering propeller.

Whenever the propeller rotates, carrying with it the ratchet levers 124, these in turn drive the eccentric strap 132 around the fixed eccentric 134 whereby the ratchet levers 124 are given an oscillating swing as indicated by the dotted lines 124—a, making two strokes per propeller revolution. The right and left hand driving ratchets 122, Figs. 2 and 10 partake of this oscillating motion and the ratchet teeth are proportioned so that the swing subtends considerably more than one but less than two ratchet teeth. With the parts in the neutral position shown i. e., with the solenoid armature 158, the control lever 160 and the control sleeve 116 in the central position under the influence of the spring 168 (neither of the solenoids 156—157 being energized) no movement is imparted to the driven ratchets 114. However, should the coil 156, for example, be energized, through the electric circuit comprising the control wire 180, the brush 178, the slip ring

176, and the connecting wires 161—159, the armature 158 will be moved to the right and the control sleeve 116 will carry the ratchets 114 to the left of Fig. 2 engaging the left hand ratchet with the driving ratchet hub 122 of the lever 124 and, accordingly, the ratchet 114 and with it the worm 100 will be advanced one tooth for each cycle of the lever 124 i. e., one tooth for each rotation of the hub.

In this specific embodiment the armature 158 has been shown as directly connected to the ratchet control lever 160 whereby the magnetic flux acting on the armature will also act as the ratchet spring, permitting the necessary slight axial movement of the ratchet for engagement of successive teeth. In the instant case the proportions are appropriate to approximately 100 teeth on the ratchet, which, accordingly, comprises the first step of a propeller operating reduction gear train giving a reduction of 100 to 1 between the rotations of the hub and of the worm 100. This is multiplied by a second large reduction between the worm 100 and the wormwheel 74 whereby the bevel gear 70 is slowly rotated whenever one of the solenoids 156—157 is energized, communicating its motion through the third reduction comprises by the propeller blade quadrant gears 68 whereby the blades are slowly moved to simultaneously increase or decrease their pitch according to which of the solenoids is energized. The worm 100 will have a very low helix angle preferably having only one lead whereby it is irreversible, that is to say, it can not be made to over-run by any force applied to the worm gear 74 so that the propeller is locked in any specific pitch position whereat the solenoids 156—157 may be de-energized.

It is well known that the forces involved in operating controllable pitch propellers are of large order, the principal resistance to be overcome being the centrifugal "flattening couple" by which the blades are urged towards the zero pitch position in operation, and added to this force is the friction on the blade bearings whenever the control is moving the blade towards increased pitch. One of the features of this invention resides in the relative ruggedness of the eccentric, lever and worm gear mechanism whereby the control forces are transmitted.

An additional feature of the invention resides in a novel lubrication system now to be described. Due to the large centrifugal forces present, trouble has been encountered in controllable propellers with leakage of the lubricant and with the centrifugal drying out of the parts near the center of rotation. As has already been said, the inwardly projecting sleeves 98 define a circumferential reservoir within the perimeter of the housing 88—90 which reservoir has no running fits since the sleeves 28 are tightly clamped into this housing and, accordingly, afford a completely oil tight structure.

Disposed at the perimeter of the housing 90, so as to be subject to the centrifugal force of the lubricant retained therein by the sleeves 98, is a small pump comprising a body 190 (Figs. 1 and 11) screwed into the housing at 192 and having a bore 194 in which operates the ball piston 196 articulated to the lever 124 at 198. The ball head of the piston over-runs inlet holes 200 on its out-stroke which creates a vacuum in the cylinder 194 assisting centrifugal force in filling cylinder with lubricant. A small non-return delivery valve 202 communicates with a passage 204 and, by means of a tube 206 and a suitable drilling 208 in the

hub 16, delivers oil to the bearing of the eccentric strap 132 wherefrom a small duct 210 leads lubricant to the ball 126 of lever 124. There is thus set up a circulation of lubricant from reservoir 5 comprised within the perimeter of the housing 88—90 to the central part of the mechanism. This system is also preferably connected through the large lightening holes 212 and a suitable drilling 214 in the hub nut 80 to lubricate the bearing bushing 76 and therefrom the wormwheel 74 and worm 100.

When it is desired to additionally incorporate the feathering feature whereby the propeller may be brought to 90° mean pitch for cruising with the engine stopped, the parts now to be described will be incorporated. It should first be mentioned that the housing 144 is provided with an internal sleeve 216 equipped with oil sealing rings 218 of the piston ring type, engaging a suitable liner 220 in the insulating rear cover 170 and within the oil tight enclosure thus formed in common with the interior of the housing 88—90 there is disposed the bevel pinion 140 engaged with the bevel gear 138 of the eccentric 134 as previously described. The pinion 140 has a shaft 222 splined at 224 into an armature shaft 226 of an electric motor 228 mounted on an extension 230 of the housing 144 by through bolts 232. The armature 234 of the motor is disposed below the center line of the fields 236, the armature being given slight axial float under the restraint of a spring 238, which normally forces the armature downwards to engage a cone clutch 240 rigid therewith, with a fixed clutch face 242 formed on the housing extension 230. By means of this spring 238, co-operating with the clutch 240, the armature 234 and the pinion 140 and eccentric 134 are held stationary during all normal operation. However, when it is desired to "feather" the propeller, the motor armature 234 is energized, and the magnetic pull from the field 236 moves the armature upwards against the spring 238 (slight play for this purpose being arranged at the upper bearing 243) and the armature is free to rotate and turn the eccentric 134 through the bevel gear 138 and pinion 140.

It will be understood that this external energization for feathering is necessary because as the "feathering" operation proceeds, the rotation of the propeller will progressively cease so that the lever and ratchet mechanism will cease to operate from the eccentric 134 if this be maintained stationary. "Unfeathering" is obviously only possible by rotation of the eccentric 134 with respect to the then stationary propeller.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. A controllable pitch propeller for an engine including in combination a hub, blades mounted thereon for pitch changing rotation, an electric motor secured to said engine, means to energize and to immobilize said motor at will, a normally stationary eccentric mounted for rotation with the hub axis and drivably associated with said motor and pitch changing gearing operatively connecting said eccentric with said blades.

2. In an engine driven propeller having blades rotatable in pitch, a control means including an

eccentric normally fixed to said engine, a cross-shaft in said propeller having right and left hand ratchets, lever means organized for oscillation upon said shaft and having companion ratchets, means to engage and disengage either pair of companion ratchets, means by which said lever is oscillated from said eccentric by rotation relative thereto, gearing operatively connecting said cross-shaft to the propeller blades, and means to rotate said eccentric for the purpose of completely "feathering" said propeller blades.

3. In an engine driven propeller having blades rotatable in pitch, a normally stationary member on the engine concentric with the propeller, pitch changing mechanism selectively connectible to the blades, in the propeller, and driven by said member, by which blade pitch changes may be effected during propeller operation by the relative movement between the propeller and engine, and independent power means for rotating said member to provide a source of power for blade pitch changes during propeller inactivity, upon effecting selective connection between the blades and the pitch changing mechanism, said power means comprising an electric motor, the means for effecting selective connection between said blades and said pitch changing mechanism comprising propeller hub carried solenoid operated clutches.

4. In an engine driven propeller having blades rotatable in pitch, a normally stationary reaction member, selectively engageable pitch changing gearing operatively connecting when engaged said blades to said reaction member, and motor means normally immobilizing said reaction member and adapted to rotate the same upon energization of said motor and upon gearing engagement to effect propeller pitch change, said reaction member comprising a cam ring on the engine and said pitch changing gearing comprising a cam follower movable with and with respect to the propeller.

5. In an engine driven propeller having blades rotatable in pitch, a reaction member, pitch changing gearing operatively connecting said blades to said reaction member, motor means normally immobilizing said reaction member and

adapted to rotate the same upon energization of said motor for feathering pitch change to stop said engine, said reaction member comprising a cam ring on the engine and said pitch changing gearing comprising a cam follower movable with and with respect to the propeller, and means to clutch the cam follower to drive the blades for pitch change.

6. In an engine driven propeller having blades rotatable in pitch; a normally stationary member journaled on the engine and coaxial with the propeller; pitch changing mechanism in the propeller driven by said member upon relative rotation between the propeller and member and including propeller carried selectively operable clutches, by which, upon clutch engagement, blade pitch changes may be effected during propeller operation with the member stationary; and motor means independent of engine operation but secured to the engine, drivably connected to said normally stationary member, selectively energizable to rotate said member to effect blade pitch changes, upon clutch engagement, when the propeller is not rotating.

7. A controllable pitch propeller for an engine including in combination a hub, blades mounted thereon for pitch changing rotation, a motor secured to said engine, means to energize and to immobilize said motor at will, a normally stationary cam member mounted for rotation on the hub axis and drivably associated with said motor, and pitch changing gearing operatively connecting said cam member with said blades, and including therein a selectively operable clutch.

8. A controllable pitch propeller for an engine including in combination a hub, blades mounted thereon for pitch changing rotation, a motor secured to said engine, means to energize and to immobilize said motor at will, a normally stationary actuating member mounted for rotation on the hub axis and drivably associated with said motor, and pitch changing gearing operatively connecting said actuating member with said blades and including therein a selectively operable clutch.

ROLAND CHILTON.
